UNITED STATES PATENT OFFICE.

ALDEN L. PUTNAM, OF LANSING, MICHIGAN, ASSIGNOR TO MOTOR WHEEL CORPORATION, OF LANSING, MICHIGAN.

METAL WHEEL.

Application filed June 19, 1924. Serial No. 721,072.

My invention relates to metal wheels and the methods of constructing them, and its purposes are to make a device by means of which the same spider or disk construction 5 may be used in either a front or rear wheel or may be used also in a single wheel or in a double wheel in which two disks or spiders are employed. A further purpose is to make a device for use with double wheels 10 such as are used on heavy trucks and the like in which the outer wheel or disk may be readily removed without loosening the inside wheel.

While I have shown and described my 15 invention as used in a wheel formed with tapering spokes as described in my application No. 639,776 filed May 18, 1923, it may be used equally well with disk wheels of any preferred type of disk without departing 20 from my invention.

I attain these purposes, by the means shown in the accompanying drawings, in which Fig. 1 shows my device as employed with a double disk wheel. Fig. 2 is a section along the line X—X of Fig. 1, the hub being removed. Fig. 3 is a diametrical section of front wheel embodying my device to illustrate the interchangeable feature.

Referring to the drawings, 1 is the hub of 30 a wheel which may be of any approved type. 2 is an integrally formed flange extended radially outwardly from the hub 1. The flange 2 is pierced with a plurality of equally spaced openings adapted to receive studs 35 for holding the wheels in position. 12 and 13 are two wheels which may be either constructed of metal spokes, secured together in the manner described in my application Serial No. 639,776 filed May 18, 1923, or by 40 welding or in any other suitable manner, or may be constructed with metal disks of any preferred type. These wheels are pierced near their hub extremities with openings of two different sizes, 5 and 11, which alternate 45 with each other. These openings are as many as the number of openings for studs provided in the flange 2, and are so arranged diametrically in each wheel that when the wheel is reversed so that what was previously 50 the outside becomes the inside, openings of the same size will occupy the same relative position that they did before the reversal; that is, after reversal a large opening will

occupy the same position that a large opening did before the reversal and a small opening the same position that a small opening did before the reversal. It follows from this that a reversal of either, or both, of the wheels will leave the stud openings in the wheels in the same relative position with reference to the stud openings in the hub. Where two wheels are to be employed as in Fig. 1, making a double wheel, the inner wheel is held in position by studs 3, which are provided with collars 4 adapted to fit the openings 5 in the inner wheel. The openings 11 in the outer wheel are large enough to receive the nut 6 of the studs 3. By this means it is possible to remove the outer wheel without in any way interfering with the inner. Since the only purpose of the studs 3 is to hold the inner wheel in position, when the outer is removed, it is not necessary to have as many of them. I prefer to use three, as shown in Fig. 2 but any other number of studs 3 and openings 11 capable of alternating with the other openings and of being symmetrically arranged, as above described, may be employed. If three are used, as shown in the drawings, then it is manifest that each alternate one of the openings 5 will be left unfilled when the inner wheel is in position.

As already stated, both wheels are pierced with duplicate sets of openings. For convenience in description I have arranged these openings in three sets numbered respectively 5, 9, and 11. The openings 5 and 9 are preferably of the same size, the openings 11 being larger in order to receive the nuts 6 of the studs 3. If desired, however, the openings 5 and 9 may be of different sizes. Indeed all the openings may be the same size, it being only essential that means should be provided for attaching the inner wheel separately to the hub flange in such manner that it shall not prevent either the reversal of the wheel or the attaching of the second wheel outside of the first. If different sizes are used the openings 5 need only be sufficient in number, preferably three, to retain the wheel in position. Any other number, however, may be employed provided it can be symmetrically arranged on both sides of the diameter of the wheel so as to permit a reversal.

It will be understood that the term "stud" as applied herein to the fastening means employed is used in a generic sense to include equivalent fastening devices such as nuts, bolts, lag-screws, and the like.

I claim as my invention and desire to secure by Letters Patent:

1. The combination with a hub having a flange, of two wheels adapted to be interchangeably attached side by side to said flange and each provided near its hub opening with a series of openings, and separate securing means including sets of studs to cooperate with the series of openings providing for detachably securing the wheels to the hub flange one independently of the other and for the removal of one of the wheels without loosening the securing means of the other.
2. The combination with a hub having a flange, of two wheels adapted to be interchangeably attached side by side to said flange and each provided near its hub opening with a series of openings symmetrically arranged thereabout, and separate securing means for detachably securing the wheels side by side to the hub flange including sets of studs cooperating with the series of openings providing for detachably securing either wheel in an inner position to the hub flange independently of the other and for the removal of the outer wheel without loosening the securing means of the inner wheel.
3. The combination with a hub having a flange, of two wheels adapted to be attached side by side to said flange and each provided near its hub opening with a series of openings, and separate securing means including sets of headed studs to cooperate with the series of openings providing for detachably securing the wheels to the hub flange side by side one independently of the other and for the removal of the outer wheel without loosening the securing means of the inner wheel, the outer wheel having openings to accommodate the heads of the securing means for the inner wheel.
4. The combination with a hub having a flange, of two wheels adapted to be attached side by side to said flange and each provided near its hub opening with a series of openings symmetrically arranged thereabout, and separate securing means for detachably securing the wheels to the hub flange including series of headed studs cooperating with the series of openings providing for detachably securing either wheel in an inner position to the hub flange independently of the other and for the removal of the outer wheel without loosening the securing means of the inner wheel, said wheels each having openings to accommodate, when used as an outer

wheel, the heads of the securing means for the inner wheel.

5. The combination with a hub having a flange, of two wheels adapted to be attached side by side to said flange, each wheel being provided near its hub opening with a series of different sized openings symmetrically arranged thereabout, and separate securing means for securing the wheels to the hub flange including headed studs cooperating with the series of openings providing for detachably securing either wheel in an inner position to the hub flange independently of the other and for the removal of the outer wheel without loosening the securing means of the inner wheel, the larger of said series of openings being adapted to accommodate the heads of the securing means for the inner wheel.

6. A wheel adapted for assembly with the hub flange of a vehicle, comprising a wheel body provided near its hub opening with a plurality of different series of openings symmetrically arranged thereabout, and independent means cooperating alternatively with a different series of openings providing for detachably securing the wheel to the hub flange in reverse positions.

7. A reversible wheel adapted for assembly in interchangeable relation with a hub flange, comprising a wheel body provided in symmetrical relation about its center with a plurality of series of openings to accommodate detachable securing lugs, one series serving in one position of the wheel and another series in a reverse position of the same.

8. A reversible wheel adapted for assembly in interchangeable dual relation with a hub flange, comprising a wheel body provided in symmetrical relation about its center with a plurality of series of openings, one series serving for attaching lugs when used as an outer wheel, another series for independent attaching lugs when used as an inner wheel, and a third series to accommodate when used as an outer wheel the ends of the securing lugs for the inner wheel.

9. A reversible wheel adapted for assembly in interchangeable dual relation with a hub flange, comprising a wheel body provided in symmetrical relation about its center with three series of openings, the three series being of different sizes, the intermediate series serving to accommodate the attaching lugs for both wheels, the smallest series to accommodate lugs for independent attachment of the inner wheels, and the largest series to accommodate within the outer wheel the heads of the attaching studs of the inner wheel.

ALDEN L. PUTNAM.
